THERMOELECTRIC SYSTEM FOR REMOTE OBJECT IMAGES

Robert Harvey Rines, Brookline, Mass.

Application July 18, 1945, Serial No. 605,721

24 Claims. (Cl. 343—17)

1

The present invention relates to electric systems, and more particularly to radio-receiving systems that, while having more general fields of usefulness, are especially adapted for use in television.

An object of the invention is to provide a new and improved radio-receiving system.

Another object is to provide a new and improved television system.

Another object is to provide a novel combined radio-and-television system.

Another object of the present invention is to provide a new and improved radio-locator system for both detecting the presence of a body and rendering it visible.

Other and further objects will be explained hereinafter and will be more particularly pointed out in the appended claims.

The invention will now be more fully explained in connection with the accompanying drawings, in which Fig. 1 is a diagrammatic view of circuits and apparatus arranged and constructed in accordance with a preferred embodiment thereof, showing also the airplane object from which the radio waves are reflected and scattered to the receiving system; Fig. 2 is a section of a modification, upon a smaller scale, taken upon the line 2—2 of Fig. 1, looking in the direction of the arrows; and Fig. 3 is a view of a common thermocouple analogous to the form shown in Figs. 1 and 2.

An electromagnetic-wave generator 4 is shown exciting a dipole 2 to produce ultra-high-frequency microwave radio energy, say, of 3 or 1.5 centimeters wave-length. A continuous-wave or any other type of modulated-wave generator may be employed, though pulsed energy, at present, has the advantage of economical and easy high-power ultra-high-frequency generation.

The waves emitted by the dipole 2 may be directed by a reflector 3 upon a parabolic reflector 6. The parabolic reflector 6 is shown directing the waves toward an object, say, an airplane 9, from which they are reflected and scattered toward a receiving station.

At the receiving station, the radio waves thus reflected and scattered from the object 9 may be focused by an electromagnetic dielectric lens 5, such as polystyrene, upon a bank or array 7, comprising a plurality of normally ineffective insulated radio-receiving pick-up unit antenna elements. The dielectric lens 5 may be replaced by any other type of well-known lens, mirror or other directive system for focusing the electromagnetic energy scattered and reflected from the

object 9 on the bank or array 7 of antenna elements.

The pick-up elements may be in the form of thermoelectric devices operating according to the Seebeck effect. Two such elements are illustrated in Fig. 3, constituted of two dissimilar metal elements 10 and 11 of, say, Eureka and copper or steel. They are joined together by any well-known thermocouple solder-connecting element 8. The elements 10 and 11 are shown respectively provided with dipole segments 30 and 31.

These dipoles will receive a transmitted electromagnetic wave, whereupon heat will be produced with differential effects in the elements 10 and 11, resulting in an unidirectional thermoelectric electromotive force in electrode terminals 40 and 41 of the respective thermocouple elements 10 and 11. The radio frequency will be short-circuited in the dipoles 30 and 31, but a direct current will be caused to travel in the conductor extensions 40 and 41. Radio frequency energy on the left-hand side of the junction 8, therefore, is converted into direct current in the terminals 40 and 41 on the other side. A mechanism is thus provided for rectifying the radio frequency energy. As described in the Admiralty Handbook of Wireless Telegraphy, 1938, section W, paragraph 6, the electromotive force is proportional to the temperature and the heating to the square of the radio-frequency current.

The thermoelectric antenna elements are shown arranged in the form of rows and columns, in the proximity of the focal plane of the lens 5. The first or uppermost row of the bank, for example, is illustrated as comprising the thermocouples 10—11, 12—13, 14—15, 16—18, etc., shown as equally spaced horizontally. The length of the segments 10—11, etc., up to the junctions 8, may be a quarter-wave length each. The second row from the top is shown comprising the sections 22—24, 28—29, etc. Though only a small number of antenna units is shown in each row, this is merely for illustrative purposes, in order not to confuse the disclosure. It will be understood that, in practice, a large number of antenna units will be employed in each row. In order to fix the ideas, for purposes of description, let that number be chosen as 180.

The columns and rows are separated by the insulation strips 1. Though each column is shown as comprising only a few antenna units, this is again in order not to complicate the drawings. In actual practice, the number of antenna strips in each column may be quite large, say 180.

The direct-current sides of the thermocouples are shown disposed in a long illuminating cell such as a neon or other gas cell, directly behind the pick-up elements of the corresponding row, and extending substantially throughout the length of the row. In this case, portions of the neon-gas-discharge cells are each associated with and correspond to one of the antenna elements, energization of which by the received radio-frequency energy will produce a likeness on the array of cells corresponding to the energy received by the corresponding antenna elements.

Each of these cells may be hermetically sealed, and may contain a suitable gas, such as neon, to constitute a gas cell. A screen 50, disposed at the rear faces of the cells, may be constituted of darkened transparent material to serve as a suitable weak filter. If neon is the gas employed, the filter preferably should be orange-colored.

Electrodes are shown mounted at the ends of the cells to provide initial striking voltages for the gas cells. An initial glow may be produced in the top cell 23 by impressing a low direct-current potential upon the electrode 20, compared to that of the electrode 19.

An initial glow may similarly be produced in the second cell 33 by impressing a low direct-current potential upon the electrode 26, as compared with the potential impressed upon the electrode 25; and so on for other correspondingly positioned electrodes. The pairs of electrodes are shown connected in parallel across a battery 27 for permanently impressing these direct-current striking potentials. A glow discharge will thus be established through the various gas-discharge neon cells between the said electrodes.

The thermoelectric antenna-section units will, of course, all receive the reflected or scattered radio waves through the lens 5 simultaneously. There will be focused on each antenna section a radio-frequency voltage corresponding to the scattering from a corresponding area of the object 9.

The pick-up elements will thus receive different field strengths of reflected or scattered radio energy, corresponding to the amount of energy reflected or scattered from the various parts of the object 9 and converged upon the array of pick-up elements by the lens 5. A radio-energy picture of the object 9 is thus recorded upon the array, specific elemental areas of which will correspond to specific elemental areas of the object 9, and this specific-elemental-area correspondence will be preserved by reason of the fact that there is no discharge between the thermo-electric-couple antenna elements. By means of the present invention, this radio-energy picture may be converted into a faithful visible picture. The present invention, however, is to be contrasted with prior-art proposals for converting radio energy into a visual indication by causing radio-receiving elements to produce radio-frequency discharges between one another, thereby destroying such specific-elemental-area correspondence and distorting any possible visible likeness.

The received radio energy, by the Seebeck effect, will produce corresponding direct-current voltages continuously to disturb or modify the normal relation between the electrodes 19-20, 25-26, etc., of the gas cells in which they are disposed. The glow through the various portions of the neon cells will become correspondingly modified in accordance with the direct-

current voltage produced from the radio-frequency energy received by the corresponding antenna elements.

By suitable design, it is possible to operate on a portion of the characteristic of the neon cell such that a nearly linear relationship shall exist between the direct-current excitation and the illumination or glow intensity of the neon cells, within the range of operation. The radio distribution received by each thermo-couple radio-receiving element may therefore be converted, according to the present invention, into a corresponding light distribution.

To fix the ideas, consider the cell 23, for example, where a direct-current potential is established by the battery 27 between the electrodes 19 and 20. This causes ionization of the neon and a slight orange glow between the electrodes 19 and 20. The impressing of radio-frequency energy on the dipole 10-11, converted into direct-current voltage by the thermocouple thereof, will cause the part of the neon cell associated with the conductor extension electrodes 40 and 41 on the other side of the thermocouple 10-11 to glow with an additional modifying orange glow the intensity of which bears a fixed relation to the amount of radio-frequency energy.

Unlike the before-mentioned prior-art systems, there will be little or no interference between the glows in the cells behind adjacent antenna sections, because the gas-glow or discharge boundaries between the direct-current side of the antenna sections, such as those between the electrodes 40 and 41, are rather sharply defined, and only direct-current voltages are present in the gas. The discharges are at right angles to the background discharge in the cells, as between the electrodes 19 and 20. The slightly darkened aspect produced by the orange-colored filter 50 will help to keep the daylight off the gas, thus preventing affecting the ignition characteristics. The weak orange filtering action serves also to help produce the additional orange glow in response to the radio-frequency signals, filtering out the background of the orange direct-current glow, and thus helping to produce on the bank of neon cells the visible image of the object 9, as impressed, in radio-frequency form, on the antenna sections.

Separate neon tubes may, however, be employed, with separate cathodes, connected to the respective radio-receiving elements. A uniform background may be attained in this manner. The picture of the object 9 would be visible on the neon cells themselves, if such separate cells were employed. Instead of the direct-current ignition potential from the battery 27, moreover, a striking radio-frequency voltage, suitably attenuated, may be applied to the cells from the transmitter 4. The neon cells may, furthermore, be supplied with control-grid electrodes and anodes, omitted from the drawings, for the sake of simplicity. If the radio-frequency signals should be weak, they may be enhanced by means of amplifiers between the antennas and the neon cells. A radio-frequency shield 51 of any suitable material, such as mesh wire, may be interposed between the cells and the pick-up elements 10-11, etc., to lessen the likelihood of interference effects of the radio energy and the electrodes and elements in the cells.

A likeness corresponding to the radio energy received by the radio-receiving array 7 of antennae will thus be electromagnetically produced on the screen of the gas-discharge neon cells.

This likeness will be a distinct, definite sharp visible image of the distant object. The definition of the likeness depends merely upon the size of the thermoelectric elements and their number. The greater the number of the elements, and the smaller their size, the more sharp will be the definition. 180 rows and columns of antenna sections of dipole dimensions will yield good definition for large close-range objects, particularly for a three-centimeter wave, assuming an eight-foot screen 50.

Although the invention has been described in connection with antennae arranged in rows and columns, it will be understood that this is not essential, for other arrangements are also possible. Antennae arranged along concentric circles covering the field, or a continuous spiral, will also serve.

Further modifications will occur to persons skilled in the art, and all such are considered to fall within the spirit and scope of the invention, as defined in the appended claims.

What is claimed is:

1. An electric system having, in combination, means for receiving radio waves, gas-discharge means, and thermoelectric-couple means controlled in accordance with the thermoelectric operation of the thermoelectric-couple means for producing on the gas-discharge means direct-current glow discharges defining a likeness corresponding to the energy distribution received by the radio-receiving means.

2. An electric system having, in combination, a plurality of thermoelectric-couple radio-wave receiving elements, gas-discharge means having portions each corresponding to one of the elements, and means controlled in accordance with the thermoelectric operation of the radio-wave receiving elements for energizing the said portions of the gas-discharge means in accordance with the thermoelectricity in each of the elements resulting from energy received by each of the elements to produce a likeness corresponding to the energy received by each of the elements.

3. An electric system having, in combination, thermoelectric-couple means for receiving radio waves from an object, gas-discharge means, and means operable in accordance with the thermoelectric operation of the thermoelectric means and responsive to the thermoelectricity in the thermoelectric-couple means and controlled by the received radio waves for producing on the gas-discharge means a likeness of the object.

4. An electric system having, in combination, a plurality of thermoelectric-couple radio-wave receiving elements, gas-discharge means having portions each corresponding to one of the elements, means for striking glow through the gas-discharge means, and means for modifying the glow of the said portions of the gas-discharge means in accordance with the thermoelectricity in each of the elements resulting from the radio-frequency energy received by each of the elements.

5. An electric system having, in combination, a plurality of radio-wave receiving elements, electrode means, means for producing a glow discharge between the electrode means, and means for modifying the glow discharge between the electrode means with direct-current glow discharges in accordance with the energy received by each of the elements.

6. An electric system having, in combination, a plurality of thermoelectric couples for receiv-

ing radio waves from an object, each thermoelectric couple corresponding to an elemental portion of the object from which it receives the radio waves, and gas-discharge means responsive to the thermoelectricity produced in each of the thermoelectric couples by the radio waves from the corresponding elemental portions of the object for producing elemental portions of a likeness of the object corresponding to the radio waves received by each of the corresponding thermoelectric couples.

7. An electric system having, in combination, a thermoelectric couple comprising two elements of dissimilar metals for receiving radio waves and an electrode connected to each of the elements, the elements having dimensions resonant to the radio waves, and gas-discharge means responsive to the energy produced in the electrodes by the received radio waves for producing a visual indication of the received radio waves.

8. An electric system having, in combination, a plurality of radio-wave receiving-and-rectifying elements for receiving and rectifying radio waves from an object, gas-discharge means, and means connecting the elements and the gas-discharge means for producing rectified direct-current discharges in the gas-discharge means, thereby to produce a likeness of the object.

9. An electric system having, in combination, a plurality of thermoelectric-couple elements for receiving and rectifying radio waves from an object, gas-discharge means, and means connecting the elements and the gas-discharge means for producing rectified direct-current discharges in the gas-discharge means, thereby to produce a likeness of the object.

10. An electric system having, in combination, a plurality of thermoelectric-couple elements for receiving and rectifying radio waves from an object, each thermoelectric-couple element corresponding to an elemental portion of the object from which it receives the radio waves, and gas-discharge means responsive to the rectified energy produced in the thermoelectric-couple elements by the radio waves from the corresponding elemental portions of the object for producing elemental portions of a likeness of the object corresponding to the radio waves received and rectified by the corresponding elements.

11. An electric system having, in combination, a plurality of radio-wave receiving elements for receiving radio waves, gas-discharge means having two electrodes, means for striking a first gas-glow discharge between the electrodes, and means connecting the radio-receiving means and the gas-discharge means for producing modifying gas-glow discharges at right angles to the said first gas-glow discharge in accordance with the radio waves received by the radio-wave receiving elements.

12. An electric system having, in combination, thermoelectric-couple means comprising two elements of dissimilar metals having a common junction, means for focusing radio waves from an object upon the thermoelectric-couple means, and gas-discharge means connected to the common junction and responsive to the thermoelectricity in the thermoelectric couple means for producing a likeness of the object.

13. An electric system having, in combination, a plurality of first bimetal thermocouples resonant to radio waves for receiving radio waves from an object, a plurality of second bimetal thermocouples, one corresponding to each of the first thermocouples, means for impressing

Upon each second thermocouple the voltage of the corresponding first thermocouple and means is controlled in accordance with the thermoelectricity produced in the second thermocouples in response to the radio waves received by the first thermocouples for producing a likeness of the object corresponding to the radio energy received by the first thermocouples from the object.

14. An electric system having, in combination, thermoelectric-couple means for receiving radio waves, gas-discharge means, means for producing a background gas discharge through the gas-discharge means, means controlled by the received radio waves for modifying the background of the gas discharge, and means for filtering out the unmodified background gas discharge.

15. An electric system having, in combination, thermoelectric-couple means for receiving radio waves, gas-discharge means, means for striking a sufficient background gas discharge through the gas-discharge means to operate the gas-discharge means in accordance with a characteristic curve provided with a substantially linear portion along which the intensity of illumination of the gas varies substantially linearly with the intensity of excitation energy, and means controlled by the received radio waves and operative on the linear portion of the characteristic curve for modifying the background gas discharge.

16. An electric system having, in combination, a two-dimensional array of gas-discharge elements, and thermoelectric-couple radio-receiving means for receiving radio waves from an object and connected to and cooperative with the gas-discharge elements to produce a likeness of the object.

17. An electric system having, in combination, a plurality of thermoelectric-couple radio-wave receiving elements for simultaneously receiving radio waves from an object, illuminating means, and means for permanently electrically connecting the radio-wave receiving elements to the illuminating means continuously to control the illumination of the illuminating means in accordance with the thermoelectricity produced by the received radio waves in the radio-wave receiving elements, in order to produce a likeness of the object upon the illuminating means simultaneously with the reception of the radio waves by the radio-wave receiving elements.

18. An electric system having, in combination, a plurality of radio-wave receiving-and-rectifying elements for receiving and rectifying radio-wave energy from an object, illuminating means, and means for permanently electrically connecting the radio-wave receiving-and-rectifying elements to the illuminating means continuously to control the illumination of the illuminating means in accordance with the rectified energy produced by the radio waves in the radio-wave receiving-and-rectifying elements in order to produce a likeness of the object upon the illuminating means simultaneously with the reception of the radio waves by the radio-wave receiving-and-rectifying elements.

19. An electric system having, in combination, radio-wave receiving means for receiving radio waves from an object comprising antenna means provided with electrical conductors and gas-discharge means into which the electrical conductors extend to control the gas-discharge means

in accordance with radio waves received from the object by the radio-wave receiving means.

20. An electric system having, in combination, radio-wave receiving means for receiving radio waves from an object comprising antenna means provided with electrical conductors, gas-discharge means, and means for striking a background gas discharge in the gas-discharge means, the electrical conductors extending into the gas-discharge means to modify the background gas discharge in accordance with the radio waves received from the object by the radio-wave receiving means.

21. An electric system having, in combination, dipole antenna means for receiving radio waves from an object provided with integral electrical conductors and gas-discharge means into which the electrical conductors extend to control the gas-discharge means in accordance with the radio-wave energy received from the object by the radio-wave receiving means.

22. An electric system having, in combination, radio-wave receiving means for receiving radio waves from an object comprising thermoelectric-couple means provided with electrical conductors and gas-discharge means into which the electrical conductors extend to control the gas-discharge means in accordance with radio waves received from the object by the radio-wave receiving means.

23. An electric system having, in combination, radio-wave receiving means for receiving radio waves from an object comprising thermoelectric-couple means provided with electrical conductors, gas-discharge means, and means for striking a background gas discharge in the gas-discharge means, the electrical conductors extending into the gas-discharge means to modify the background gas discharge in accordance with the radio waves received from the object by the radio-wave receiving means.

24. An electric system having, in combination, a plurality of thermoelectric-couple radio-wave receiving elements for receiving radio waves, means for focusing radio waves from an object upon the radio-wave receiving elements, illuminating means electrically connected to each element, means for illuminating the illuminating means, and means controlled in accordance with the radio waves received by the radio-wave receiving elements for controlling the intensity of illumination of the illuminating means to produce a likeness of the object.
